UNITED STATES PATENT OFFICE

HAROLD A. BURT, OF ST. ALBANS, NEW YORK, ASSIGNOR TO MERGENTHALER LINOTYPE COMPANY, A CORPORATION OF NEW YORK

KNIFE WIPER

Application filed July 21, 1931. Serial No. 552,145.

This invention relates to slug casting machines, such as linotype machines of the general organization represented in U. S. Letters Patent to O. Mergenthaler, No. 436,532, 5 wherein circulating matrices are released from a magazine in the order in which their characters are to appear in print and then composed in line, the composed line transferred to a vertically movable transporter or 10 first elevator which presents it to the mold, the mold filled with molten metal to form a slug or linotype against the matrices which produce the type characters thereon, and the matrices thereafter elevated and returned 15 through a distributing mechanism to the magazine from which they started. At the time the matrices are being elevated and distributed, the cast slug is ejected from the mold and forced between a pair of trimming 20 knives mounted on the vise frame and which dress down the sides of the slug and bring it to the proper thickness.

In these machines, it is necessary at times to vary the vertical position of the first elevator during casting in order to bring about the proper alignment of the matrix characters with the mold slot. For instance, in the use 25 of matrices bearing characters up to 14 pt., the elevator is ordinarily allowed to descend 30 to its lowermost level, whereas, in the use of matrices with characters ranging from 14 pt. to 42 pt., the elevator is arrested at a slightly higher level. In recent years, improvements have been made to adapt the machine 35 to handle matrices with characters above 42 pt. and as high as 60 pt. and more, so that it has been necessary in the use of such matrices to arrest the elevator at a still higher 40 level. For arresting the elevator at its higher levels, the vise frame is ordinarily provided with two pivoted filler pieces or stop members, so constructed and arranged that either 45 may be swung into or out of operative position as desired, their construction and mode of operation being fully described in U. S. Letters Patent to D. S. Kennedy, No. 1,595,947.

In these machines, it is also the practice to 50 remove the shavings from the knives after a

slug has been trimmed and before the next slug is delivered therethru, and this is ordinarily accomplished by the use of a knife wiper which is controlled or actuated by the movement of the first elevator, either in its descent or in its ascent. However, when the knife wiper is actuated by the downward movement of the first elevator and the elevator is arrested at its upper casting levels, the 55 wiper fails to make a complete wiping stroke (i. e. fails to travel the full length of the knife blades), and hence in casting full length slugs, some of the shavings are not removed from the knife blades and give rise to the undesirable features which the wiper was originally intended to eliminate. 60

The present invention contemplates an arrangement whereby the stroke of the knife wiper may be kept constant, regardless of the level at which the elevator is arrested. To 70 this end, specifically, the elevator is provided with a pivotally mounted lever, one arm of which is adapted to actuate the knife wiping mechanism, and the other arm of which is provided with an adjustable pin which is set to strike the vise frame shortly before the elevator comes to rest, thereby causing the lever arm to rock about its pivot a predetermined distance necessary to give a full stroke to the knife wiper. 75

In the accompanying drawings, the invention is shown merely by way of example and in preferred form, and obviously many changes and variations may be made therein which will still be comprised within its spirit. It should be understood, therefore, that the invention is not limited to any specific form or embodiment, except insofar as such limitations are specified in the appended claims. 85

Referring to the drawings:

Fig. 1 is a side elevation of the vise frame and elevator, showing the knife wiper at the beginning of its stroke, and showing the rocking lever mounted on the elevator; 90

Fig. 2 is a side elevation similar to Fig. 1, showing the elevator at its lowermost level and the knife wiper at the end of its stroke; 95

Fig. 3 is a side elevation similar to Fig. 1, showing by the full lines, the elevator at the top of its stroke and a filler piece in position 100

on the top of the vise frame to arrest the elevator at an upper level, and showing by the dotted lines the elevator arrested at its upper level and the lever rocked by the vise frame to give a full stroke to the knife wiper;

Fig. 4 is a top plan view showing the relation of the several parts to one another; and

Fig. 5 is a vertical sectional view taken on the line 5—5 of Fig. 4, showing the construction of the adjustable pin for rocking the knife wiper actuating lever.

After composition, the line of matrices M is delivered to the first elevator A, as shown in Fig. 1, and then lowered thereby to the position shown in Fig. 2 in front of the mold B carried by the rotatable disc B'. The mold disc B' immediately advances to bring the mold B into contact with the matrix line for the casting of the slug, and after the slug is cast, the mold disc is retracted and rotated to carry the mold from its horizontal casting position to a vertical position immediately in front of an ejector (not shown), which operates to expel the slug from the mold and force it between a pair of trimming knives C, whence the slug is delivered to a receiving galley (not shown) at the front of the machine. During the slug ejecting operation, the first elevator A ascends to its highest level to deliver the composed line to the distributing devices, and thereafter descends to its normal position of rest (shown in Fig. 1) in readiness to receive another composed line.

As already stated, in casting slugs from matrices bearing characters of a size greater than 14 pt., it is necessary to arrest the first elevator in its descent at levels somewhat higher than the level at which it is arrested when casting from matrices bearing characters of a size under 14 pt. Ordinarily, the elevator is arrested at its lowermost level by an adjusting pin D, depending from the underside of the elevator head A², and which strikes the top face E of the stationary vise frame E', wherein the elevator is slidably mounted as usual. In order to arrest the elevator at the higher levels, there are provided two filler pieces F and F', pivotally mounted on a rod f running transversely across the top of the vise frame. In practice, to arrest the elevator at an intermediate level, the filler piece F' is moved into the position shown by the dotted lines in Fig. 4, and to arrest the elevator at a higher level, the filler piece F is also moved into active position, the active portions f¹ and f² thereof being superimposed upon the active portions f³ and f⁴ of the filler piece F'. If more detailed information is desired, reference may be had to the Kennedy Patent No. 1,595,947 above referred to.

As illustrated in the drawings, and as embodied in the commercial linotype machines,

with a wiping blade G arranged to move along the edges of the knives, the cleaning stroke being preferably downward or as the blade G moves from the position shown in Fig. 1 to that shown in Fig. 2. The blade G is supported by a rod g, arranged at the back of the vise frame and guided in its vertical movement by a bracket g' attached to said frame. In order that the blade G will not ride directly on the cutting edges of the knives, the upper end of the rod g is formed with a projection g², adapted to bear against the body of one of the trimming knives and to slide longitudinally thereon. At its lower end, the rod g is journaled in the hub portion g⁴ of a link member g³ which connects the rod g to a similar rod g⁵ at the front of the vise frame, the connecting member g³ being rigidly and adjustably secured to the rod g⁵ by the nuts g⁶ and g⁷. A coiled spring s, wound about the hub g⁴ and bearing against the rod g, tends constantly to hold the wiper blade in proper relation to the trimming knives.

The wiping blade G is held in its normal or raised position by a compression spring g⁸ surrounding the rod g⁵ and arranged between two fixed brackets H and H' on the stationary vise frame E', the upper or free end of the spring bearing against an adjusting nut g⁹ carried by the rod g⁵ and separated from the bracket H' by a collar g¹⁰. For operating the knife wiper, there is ordinarily provided a pin J, projecting from the elevator A and adapted to strike the top of the rod g⁵ as the elevator A descends, whereby the wiper is forced downward against the pressure of the compression spring g⁸, which later raises the wiper back to its upper normal position as the elevator ascends.

The movement of the elevator when it descends to its lowest casting level is just enough to impart a full stroke to the knife wiper (see Figs. 1 and 2), and it is obvious, therefore, that when the elevator is arrested at one or another of the higher casting levels, the wiper blade G will fail completely to traverse the cutting edges of the knives C and hence, when full length slugs are being cast, will fail to clean the lowermost ends of the knives.

The simple expedient provided by the present invention for obviating this undesirable feature consists of a lever O pivotally mounted on the first elevator A as at O'. One arm o of the lever O is arranged between the pin J and the rod g⁵, while the other arm o' of the lever is provided with an adjustable pin P, adapted to be set in different positions thereon according to the level at which the first elevator is to be arrested. Except when the elevator descends to its lowermost level, the pin P is set to strike against the top face E of the vise frame E' just before the elevator A comes to rest, whereby the lever O

is rocked about its pivot O' and the movement of the elevator multiplied sufficiently to impart a full stroke to the knife wiper.

As a suitable mounting for the pin P, the 5 arm o' of the lever O is formed at its end with a cylindrical boss P' in which the pin is slidably arranged. In order to hold the pin P in position within the boss, there is provided a bolt p (see Fig. 5) screwed to the 10 pin P and passing through a longitudinal slot o² cut through the wall of the boss P', the screw bolt p being provided with a knob or handle p' containing a compression spring p² which tends constantly to move the knob 15 inwardly on the screw bolt. The longitudinal edges of the slot o² are formed with opposed notches o³, which form with the slot a series of superposed circular openings o⁴ of a size to accommodate the inner end p³ of the knob p'. With this arrangement, it is 20 possible, after pulling outwardly on the knob p' against pressure of the spring p², to adjust the pin P upwardly or downwardly in the boss P' and then to lock said pin in its 25 adjusted position by releasing the knob and allowing its inner end p³ to engage in one or another of the circular openings o⁴. Since the elevator herein is intended to be arrested at only three different levels, provision has 30 been made for setting the pin P in as many different positions only. It hardly needs to be stated that the number of different positions of the pin P could be readily increased to accord with the number of different levels 35 at which the elevator is to be arrested. In order that a finer adjustment of the multiplying action of the lever O may be had, the pin P (Fig. 5) is provided with a screw p⁴, which may be adjusted to protrude more or 40 less therefrom.

The operation of the parts will now be clear: The elevator A, having received a composed line of matrices M, positions the same in proper casting relation to the mold B. If the matrices bear characters less than 45 14 pt. in size, the elevator is permitted to descend to its lowermost level, as in Fig. 2, in order to aline the matrix characters with the mold slot b, and hence the pin P is set in its uppermost position in the boss P' as 50 shown. In the descent of the elevator, the arm o of the lever O, which in this example acts merely as an interponent between the pin J and the upper end of the rod g⁵, causes the latter to move downward against the 55 pressure of the compression spring g⁸ until the elevator is arrested by contact of the pin D with the top E of the vise frame E', and this downward movement of the rod g⁵ is 60 sufficient to cause the knife wiping blade G to traverse the entire length of the knife edges, or in other words, (because of the full descent of the elevator) to make a complete 65 wiping stroke (compare Figs. 1 and 2).

If, however, as a further example, the

matrices carried by the elevator should happen to be of a size greater than 42 pt., both 70 filler pieces F and F' are swung into active position, as in Fig. 3, and the elevator will therefore be arrested in its descent at its uppermost level as indicated by the dotted lines in Fig. 3, due to the fact of course that the pin D strikes against the filler pieces rather than directly on the top of the vise frame. The actual movement of the elevator is consequently less than in the former example, and hence, to compensate for this, the pin P is set in its lowermost position within the 75 boss P' as shown in Fig. 3. As a result, just before the elevator is arrested by the pin D, the lower end of the pin P will strike against the top E of the vise frame E' and rock the lever O counterclockwise about its pivot O', causing the arm o to depress the rod g⁵ away from the pin J for a distance sufficient to 80 complete the stroke of the wiper G (see the dotted line showing in Fig. 3).

If the line of matrices bear characters ranging between 14 pt. and 42 pt., only the 85 one filler piece F' is moved into active position for the arrest of the elevator at an intermediate level, and to compensate for the incomplete descent of the elevator in this case, the pin P is set in its intermediate position in the boss P', the lever O being rocked to a 90 less extent than before but sufficiently to complete the stroke of the wiper G.

Having thus described my invention, what I claim is:

1. In a slug casting machine, the combination of a line transporter, means for varying the casting position of the transporter, slug trimming knives, means for cleaning the knives, and operative connections between the transporter and the knife cleaning means, said 100 connections including an adjustable element carried by the transporter and arranged to engage a stationary part of the machine whereby the extent of the knife cleaning action may be kept uniform regardless of the 105 casting position of the transporter.

2. In a slug casting machine, the combination of an elevator, adjustable means for arresting the elevator at one or another of different casting levels, a pair of slug trimming 110 knives, a wiper associated with the knives, and operative connections between the elevator and the knife wiper whereby the active or wiping stroke of the latter is imparted thereto by the downward movement of the elevator, said connections including an adjustable actuating element carried by the elevator and arranged to engage a stationary 115 part of the machine and adapted to be set in one or another of different positions according to the level at which the elevator is to be arrested, whereby the wiping stroke of the knife wiper may be kept uniform.

3. In a slug casting machine, the combination of an elevator, adjustable means for ar- 120

resting the elevator at one or another of different casting levels, a pair of slug trimming knives, a wiper associated with the knives, and operative connections between the elevator and the knife wiper whereby the active or wiping stroke of the latter is imparted thereto by the downward movement of the elevator, said connections including a pivoted actuating lever carried by the elevator and provided at one end with an adjustable element arranged to engage a stationary part of the machine and adapted to be set in one or another of different positions according to the level at which the elevator is to be arrested, whereby the wiping stroke of the knife wiper may be kept constant or uniform.

4. In a slug casting machine, the combination of an elevator, adjustable means for arresting the elevator at one or another of different casting levels, a pair of slug trimming knives, a wiper associated with the knives, and operative connections between the elevator and the knife wiper whereby the active or wiping stroke of the latter is imparted thereto by the downward movement of the elevator, said connections including a pivotally mounted actuating lever carried by the elevator, one arm of said lever being formed with a cylindrical boss housing an adjustable pin adapted to contact with a stationary part of the machine before the elevator comes to rest in its casting position.

5. A combination as in claim 4, wherein the wall of the cylindrical boss is formed with a longitudinal slot and a series of opposed notches cut in the edges of said slot so as to form with the slot a series of openings, and wherein the adjustable pin is provided with a locking detent adapted to engage in one or another of said openings.

6. A combination as in claim 4, wherein the wall of the cylindrical boss is formed with a longitudinal slot and a series of opposed notches cut in the edges of said slot so as to form with the slot a series of openings, and wherein the adjustable pin is provided with a locking detent to engage in one or another of said openings, said detent being in the form of a spring actuated knob slidably mounted on a bolt or the like attached to the pin and projecting through the slot in the boss.

7. A combination as in claim 4, wherein the adjustable pin is provided with an adjusting screw projecting beyond the lower end thereof.

8. In a slug casting machine, the combination of an elevator, adjustable means for arresting the elevator at one or another of different casting levels, a pair of slug trimming knives, a wiper associated with the knives, operative connections between the elevator and the knife wiper whereby the active or wiping stroke of the latter is imparted thereto by the downward movement of the elevator, said connections including a vertically disposed

rod slidable in fixed guides and connected to the knife wiper, a spring connected to the rod and serving normally to move it upwardly, and adjustable means on the elevator for engaging the rod in the descent of the elevator and moving the rod downwardly to actuate the knife wiper.

9. In a slug casting machine, the combination of an elevator, adjustable means for arresting the elevator at one or another of different casting levels, a pair of slug trimming knives, a wiper associated with the knives, operative connections between the elevator and the knife wiper whereby the active or wiping stroke of the latter is imparted thereto by the downward movement of the elevator, said connections including a vertically disposed rod slidable in fixed guides and connected to the knife wiper, a spring connected to the rod and serving normally to move it upwardly, and a pivoted lever carried by the elevator for moving the rod downwardly, said lever having an adjustable pin arranged to engage a stationary part of the machine in the downward movement of the elevator.

10. In a slug casting machine, the combination of an elevator, adjustable means for arresting the elevator at one or another of different casting levels, a pair of slug trimming knives, a wiper associated with the knives, and operative connections between the elevator and the knife wiper whereby the active or wiping stroke of the latter is imparted thereto by the downward movement of the elevator, said connections including a vertically disposed rod slidable in fixed guides and connected to the knife wiper, a coil spring surrounding said rod and bearing at its lower end on one of the fixed guides and at its upper or free end against a nut or collar attached to the rod, a laterally projecting pin carried by the elevator and arranged in line with the vertically disposed rod, and a centrally pivoted lever also carried by the elevator, one end of the lever being interposed between the laterally projecting pin and the upper end of the rod, and the opposite end of the lever being provided with an adjustable pin adapted to contact with a fixed part of the machine in the downward movement of the elevator.

11. In a slug casting machine, the combination of a vertically movable elevator, adjustable means for arresting the elevator at one or another of different casting levels, a pair of slug trimming knives, a wiper associated with the knives, and direct connections between the elevator and the knife wiper whereby the downward movement of the elevator will effect the downward movement of the knife wiper without multiplication, said connections including an adjustable element adapted when the elevator is arrested above

its lowermost casting level to multiply the downward movement of the knife wiper so as to impart a uniform stroke to the wiper regardless of the raised level at which the elevator is arrested.

In testimony whereof, this specification has been duly signed by:

HAROLD A. BURT.
